(57) **CLAIM**

The ornamental design for a “cookware handle holder,” as shown and described.

DESCRIPTION

FIG. 1 is a top perspective view of a cookware handle holder, showing our new design;

FIG. 2 is a side plan view of the “cookware handle holder” of FIG. 1;

FIG. 3 is a plan view of a closed end of the “cookware handle holder” of FIG. 1;

FIG. 4 is a plan view of an opposing and open end of the “cookware handle holder” of FIG. 1;

FIG. 5 is a bottom plan view of the “cookware handle holder” of FIG. 1; and,

FIG. 6 is a top plan view of the “cookware handle holder” of FIG. 1.

It is submitted that broken line illustrations of the ribs on an inside surface of the “cookware handle holder” in FIGS. 1 and 4 are not part of the design sought to be patented.
